CENTRIFUGAL PUMP

Camille Clare Sprankling Le Clair, London, England, assignor to Tecalemit Limited, Brentford, England, a corporation of Great Britain

Application January 28, 1947, Serial No. 724,817
In Great Britain January 28, 1946

17 Claims. (Cl. 103—97)

1

This invention relates to centrifugal pumps, fans or blowers and also to prime movers of the turbine type wherein the energy of the fluid is used to drive the rotor or impeller. For brevity, however, such pumps, fans, blowers and prime movers will all be referred to hereinafter simply as "centrifugal pumps."

The invention relates particularly to such pumps designed to deliver a very small quantity of fluid at a very high pressure, and in which as a result the radial velocity of flow of the fluid through the rotor or impeller is relatively small in comparison with the high tangential velocity of the rotor.

It is known that in centrifugal pumps wherein the fluid delivery is extremely small, whilst the head, and hence the speed of rotation of the rotor, is relatively high, the angle at which the fluid leaves the periphery of the rotor so nearly approaches the tangent to the rotor that the design of efficient diffusing means becomes extremely difficult if not impossible.

An object of this invention therefore is to provide a centrifugal pump in which this difficulty is overcome and which for the purpose of this description may be referred to as a "restricted output centrifugal pump."

A restricted output centrifugal pump in accordance with the present invention comprises a casing having an inlet passage and an outlet passage, a rotor rotatably mounted in the casing, a number of spaced, outwardly-running fluid passages in the rotor, the inlet ends of these passages being adapted to receive fluid from the said inlet passage, a fluid inlet restriction means, or limited fluid inlet distributor, for restricting the ingress of fluid from said inlet passage to one or more of the rotor passages while simultaneously preventing or shutting off the ingress of fluid to the remaining rotor passages which are in the majority, and a fluid outlet diffuser means which permits the egress of fluid from the, or each, rotor passage which has been or is being supplied with fluid from the said distributor means, while simultaneously preventing or shutting off the egress of fluid from the said remaining rotor passages.

For output restriction purposes, that is to say, in order to achieve the object of the invention, it is usually desirable that the said restrictor and the diffuser means shall cut off all the said rotor passages except one at a time, but at the same time, however, for balancing purposes, it is usually desirable that at least two passages shall be

2

left open and that these shall be equally spaced circumferentially.

Those rotor passages through which the egress of fluid takes place simultaneously will be referred to hereinafter as "operative passages" and it will be shown hereinafter that in cases in which, for balancing purposes, it is desirable or necessary to use at least two operative passages at a time, and in which it is also desirable or necessary, for fluid output restriction purposes, to use less than two operative passages, this effect may be achieved by arranging the restrictor and the diffuser means in such a manner that the opening and closing of the inlet and outlet ends of the operative passages do not synchronise. Thus, before the inlet end to any operative passage is fully opened, it may be arranged that the outlet end of the passage has already commenced to close, or vice versa, so that the passages become only partly operative. This arrangement will be referred to hereinafter as "desynchronisation."

In a simple constructional form of the invention, the restricted output centrifugal pump comprises a casing in which the rotor is rotatably mounted. The rotor is formed with a number of spaced, curved fluid passages, the inlet ends or ports of which open into a flat port face of the rotor which rotates in cooperation with a flat port face on a part of the casing in which, two fluid inlet passages, communicating with the fluid inlet eye, are formed. The flat port face of the said part of the casing constitutes the fluid inlet restrictor and in it are formed the two spaced outlet ends or ports of the said fluid inlet passages.

The peripheral face of the rotor runs in contact with, or in close proximity to, a circular face in the casing, and through this latter face two spaced outwardly-tapered curved diffuser passages are formed which communicate with the interior of a volute delivery chamber, the arrangement being such that the fluid fed into the rotor passages from the inlet eye and the restrictor passages is discharged into the diffuser passages and thence into the delivery chamber as the rotor rotates. The delivery chamber is of volute formation, closed at one end and communicating at its other end with the outlet passage from the casing.

In a modification the port face of the fluid inlet restrictor is cylindrical and is fitted within a recess which is formed in the rotor and constitutes the port face of the latter.

In another modification, the fluid inlet restric-

tor is made separately from the casing and it is turnably arranged between the port face of the rotor and the inlet eye in the casing. The restrictor is thus capable of angular adjustment for the purpose of desynchronisation or the reverse as will be explained more fully hereinafter.

Ports may be provided in the restrictor part of the casing, or in the separate restrictor, and in the rotor itself, whereby the interior of the casing may be put into communication with the inlet side of the pump, so that the suction of the pump may be used to evacuate the casing of fluid, thus allowing a large part of the rotor surfaces to run free of fluid friction.

Further constructional features of the invention will be described hereinafter.

One constructional form of the invention, applied to a centrifugal pump for pumping liquids is shown, by way of example, on the accompanying drawings, whereon:

Figure 1 is an elevation of one part of the pump casing with the rotor fitted therein;

Figure 2 is a transverse section of the complete pump;

Figure 3 is a transverse section of a modified pump;

Figure 3A is a fragmentary transverse section of another modified pump;

Figure 4 is a fragmentary transverse section of a pump of the type shown in Figure 2, but having an adjustable fluid inlet restrictor;

Figure 5 is a fragmentary transverse section of a pump similar to that shown in Figure 3 but having a modified form of adjustable fluid inlet restrictor; and

Figure 5A is a fragmentary transverse section of a pump similar to that shown in Figure 5.

The restricted output centrifugal pump shown in Figures 1 and 2, comprises a casing which, for convenience, is made in two parts 1 and 2 adapted to be bolted together. The part 1 of the casing is formed centrally on one side with a liquid inlet eye 3, which is coaxial with the axis of rotation of the rotor or impeller and on the other side with the double ports 15 comprising the inlet distributor. The part 2 of the casing is formed centrally with a stuffing box 8 for the shaft and, when they are bolted together, the two parts of the casing form a peripheral volute chamber 20 leading to the outlet passage 4, the axis of which is disposed at a right angle to the axis of rotation of the rotor.

The single sided rotor is in the form of a disc 5 which has a boss 6 towards the inlet side of the casing and is fixed upon a driving shaft 7 which extends out of the part 2 of the casing through a stuffing box 8. The shaft is connected to a driving means such as an electric motor or pulley, which is not shown in the drawing. The flat machined inlet face 9 of the boss 6 of the rotor facing towards the inlet eye 3 runs in contact with a flat machined face 16 on the part 1 of the pump casing. The flat inlet face 9 is formed with a number of circumferentially and equidistantly spaced liquid inlet ports 11 forming the inlet ends of a number of conveniently formed liquid passages 12 which terminate in the peripheral face 13 of the rotor disc. The face 13 is spaced by a small clearance only from a cylindrical face 14 formed partly in the part 1 and partly in the part 2 of the pump casing, which face 14 forms the inlet face of a diffuser wall which will be referred to hereinafter.

The port face 10 of the part 1 of the casing opposed to the port face 9 on the boss 6 of the

rotor disc is formed with two diametrically opposite ports 15 which form the outlet ends or ports of two fluid inlet passages connected by a forked passage 16 to the inlet eye 3. The two ports 15 are thus so spaced that they are adapted to communicate with two diametrically opposite ports of the set of inlet ports 11 in the port face 9 on the boss 6 of the rotor, while simultaneously all the other ports 11 are closed by the face 10 of the part 1 of the pump casing.

Surrounding the periphery of the rotor the two parts of the pump casing together form a diffuser wall 17 within the thickness of which are formed two diametrically opposed, curved diffuser passages 18 and 19, which taper from a small cross sectioned area at the inlet end to a larger area at the outlet end. The inlet end or port of each diffuser passage is formed in the cylindrical face 14 in the pump casing and the outlet end or port 20 communicates with the volute delivery chamber 20 in the casing, one end of which chamber is closed at 20A and the opposite end of which communicates with the outlet passage 4 in the casing. Each of the diffuser passages 18 and 19 is adapted to accept liquid at high speed from the operative rotor passage 12 which registers with it and, due to its increasing cross sectional area, to deliver it at the required lower velocity to the volute delivery chamber 20 and thus to the pump outlet.

As the rotor rotates, all the inlet ports 11 of the passages 12 of which there may be any convenient number, for example, forty, in the rotor are in turn brought into communication two at a time with the outlet ports of the two restrictor passages communicating with the inlet eye 3. Simultaneously the outlet ends of these two passages in the periphery of the rotor are put in communication with the diffuser passages 18 and 19. Two rotor passages 12 in turn thus become operative passages and each receives its quota of liquid to be delivered while all the remaining passages are masked so that they receive and deliver no liquid. In this manner, therefore, the quantity of liquid passing under given conditions of speed of rotation (that is, under a given delivery head) and radial speed of flow will be proportionately reduced, i. e., in the ratio 40 to 2 or 20 to 1. In other words, for a given delivery 45 the rate of radial flow will be increased twenty times and a ratio of speed of rotation to radial flow much more advantageous than those obtainable with unrestricted output centrifugal pumps of known types will be achieved.

In general, the speed of rotation of the rotor will be high and, even with the improved flow ratio described above, the inlets to the two diffuser passages 18 and 19 will be nearly tangential to the peripheral face 13 of the rotor, so that the angle of departure of the passages from the cylindrical surface 14, close to which the face 13 runs, will be small. Hence, for a given width (measured in a plane at right angles to the axis of rotation) of the diffuser passage, the length (measured circumferentially) of the inlet end or port of the passage will be fairly large and may, if desired, be enlarged still further, so that the outlet port of any individual operative rotor passage 12 will be in communication with the inlet port of the diffuser passage 18 or 19 during quite a large angle of rotation of the rotor. It is thus possible to ensure that there is a free passage for the liquid in a rotor passage during the whole of the time during which it is operative, i. e., while

its inlet port is open to the outlet port 15 of a restrictor passage.

On the other hand, it will be appreciated that, whereas the main object of this invention is to provide a restricted output centrifugal pump capable of working at high speeds but giving small outputs, it may be desirable deliberately to restrict the output additionally to the effect of the inlet restrictor already described. This may be done by making the liquid inlet restrictor part of the casing turnable in such a way that the timing of the opening and closing of the inlet ports 11 of the rotor passages by the restrictor passage ports 15 does not wholly coincide with the opening and closing of their outlet ports by the diffuser passages 18 and 19. This, as will be explained hereinafter, can be achieved by adjusting the angular position of the restrictor part of the pump casing. By this means, the output can be regulated through the whole range, from full output right down to zero, thus giving complete control.

In the modified construction shown in Figure 3, instead of having a flat port face 10 which cooperates with the smaller or inlet port face 9 of the rotor, the liquid inlet restrictor part of the casing is in the form of a machined, cylindrical, open ended, hollow boss 21 which fits in a central machined recess 22 in the rotor with which the inlet ports or ends of the rotor passages 12 communicate. In this construction, the two restrictor ports 23 are formed substantially at right angles to the axis of rotation of the rotor through the cylindrical wall of the hollow boss 21 of the restrictor part, and they are arranged, as in the first described construction, so that they communicate with the inlet ports of all the passages in the rotor in turn two at a time, the remainder of the rotor passages being kept closed and inoperative.

Referring to Figure 3A, instead of being open, the inner end of the restrictor boss 21 facing the rotor may be closed and formed with a wall 24, which thus prevents the liquid which enters the restrictor part through the inlet eye 3 reaching the central part of the rotor in which the shaft 7 is keyed.

The restrictor boss 21 of the restrictor part of the casing and the recess 22 in the rotor may be conical instead of cylindrical, and, similarly, the peripheral face 13 of the rotor and the inner surface 14 of the diffuser wall 17 in which it runs may also be conical.

In any pump constructed as described above, whether fitted with the modified inlet restrictor part or not, the pump casing will ultimately fill with the liquid to be pumped, and the rotor will be subject to the skin friction of the liquid.

In a further modification, therefore, also shown in Figure 3A, a small port 25 is cut through the wall of the inlet restrictor part 21 in order to put the interior of the pump casing into communication with the inlet eye 3 and inlet passage, so that the suction of the pump may be used to evacuate the interior of the casing, thus allowing a large part of the rotor surface to run free of liquid friction. A similar port 26 through the end enclosure 24 of the said inlet restrictor part and a further port 26A through the rotor itself may also be provided so that the suction of the pump may be utilised to evacuate the other parts of the casing at the front and back of the rotor.

It will be appreciated that there will inevitably be a time lag, even although small, between the entry of liquid into the operative rotor passages

12 as permitted or controlled by the opening of their inlet ports 11 by the liquid inlet restrictor ports 15 and the delivery of the same quota of liquid to the diffuser passages 18 and 19 and that, at the high speed of rotation of the rotor, this time lag which, even although it will only be a fraction of a second, will be represented by quite an appreciable angular displacement of the rotor. Hence it is desirable that the opening and closing of the rotor passage inlet ports 11 should be in advance of the opening and closing of their outlet ports in the peripheral face 13 of the rotor by the diffuser passages 18 and 19 and it is obviously also desirable that the amount of the angular displacement given should be adjustable.

Hence, in a further modification of either construction described above, the liquid inlet restrictor passages may be formed in a separate member which is mounted within, and is capable of angular adjustment relative to, the casing and thus to the diffuser passages.

In the first modified construction shown in Figure 4, instead of cooperating directly with the flat inlet port face 10 of the rotor, as described with reference to Figure 2, the flat port face 27 of the part 4 of the casing is spaced from it, and between the two flat port faces a separate liquid inlet restrictor member 28 is turnably mounted. This member is formed with an inlet passage 29 which forms a continuation of the inlet eye 3 of the casing, and is bifurcated into two inlet passages 30 and 31, the outlet ports or ends of which cooperate with the inlet ports or ends 11 of the passages 12 in the rotor.

The restrictor member 28 is turnably mounted within the casing on the axis of the rotor, and it is adapted to be turned to a desired position and then locked therein by turning and locking means which, for instance, might take the form of a worm 35 carried for rotation from the exterior of the casing by a shaft 36 and meshing with teeth 37 on the periphery of the restrictor member.

Referring to Figure 5, in this modified construction a separate open-ended cylindrical or conical distributor part 28A may be constructed in like manner for angular displacement, and fitted like the hollow boss 21 within a recess 22A in the rotor as described above with reference to Figure 3. Fig. 5A shows a modification of the construction shown in Fig. 5 in which the inner end of the restrictor boss 28A is formed with an end wall 24A. A small port 25A is cut through the wall of the inlet restrictor part 28A to put the interior of the pump casing into communication with the inlet eye 3 and inlet passage, so that the suction of the pump may be used to evacuate the interior of the casing, thus allowing a large part of the rotor surface to run free of liquid friction. A similar port 26B through the end closure 24A and a further port 26C through the rotor itself may also be provided so that the suction of the pump may be utilized to evacuate the other parts of the casing at the front and back of the rotor.

Although the rotor described above is single-sided it will be appreciated that it could be double-sided, with two sets of fluid outlet passages each cooperating with its own fluid inlet restrictor passage and with its own diffuser passage.

Although in the construction described above the inlet restrictor and the outlet diffuser each have two passages arranged so that two rotor passages are simultaneously operative, it will be

appreciated that in a modified arrangement both restrictor and diffuser may each be provided with only one passage so that only one rotor passage is operative at a time.

Alternatively, the restrictor and diffuser might be provided with three or more passages, preferably equally spaced in the circumferential direction, such that three or more rotor passages are simultaneously operative.

Again it will be appreciated that the invention is applicable to multiple or multi-stage pumps, in which two or more rotors are mounted coaxially upon the same shaft, the outlet from one pump being led to the inlet of the next so that the fluid to be pumped passes through the rotors in series.

I claim:

1. A restricted output centrifugal pump which comprises, in combination, a casing having walls defining an interior cavity with a port face at one end thereof and main inlet and outlet passages at separated positions in the walls, a rotor mounted for rotation in the cavity of said casing and having a peripheral surface and a port face contiguous to the port face of the casing, said port face of the rotor having a plurality of ports therein in spaced relationship and communicating with fluid passages in the rotor extending outwardly thereof from the rotor ports to said peripheral surface, fluid inlet restrictor means including a plurality of fluid distributing ports at spaced positions in said port face of the casing aligned for registry with the rotor ports during rotation of the rotor and connected by passages in the casing to said main inlet so as to prevent flow from the main inlet to the rotor except when the said rotor and casing ports are in communication during the rotation of the rotor, said casing walls also including a diffuser face peripheral to the cavity and contiguous to the peripheral surface of the rotor, and fluid outlet diffuser means including said diffuser face, said peripheral surface of the rotor and outwardly extending passages in the diffuser face and communicating with the main fluid outlet, said outwardly extending passages in the diffuser face being spaced in relation to the said outwardly extending passages in the peripheral surface of the rotor so that there is flow therethrough to the main outlet from only the latter mentioned outwardly extending passages which have been supplied from said fluid distributing ports.

2. A restricted output centrifugal pump as defined in claim 1, and wherein said fluid distributing ports are at substantially diametrically opposed positions with respect to the rotor.

3. A restricted output centrifugal pump as defined in claim 1, and wherein said restrictor means includes an element movable with reference to the casing for varying the output of the pump.

4. A restricted output centrifugal pump as defined in claim 1, and wherein the relative positions of the outwardly extending passages in the diffuser face and the casing ports are such that the opening and closing of the casing ports corresponds only in part to the opening and closing of the outlet ends of the rotor fluid passages by the diffuser face and said outwardly extending passages.

5. A restricted output centrifugal pump as defined in claim 1, and wherein said fluid distributing ports are paired and so disposed that diametrically opposed ones of said rotor ports are opened simultaneously to the said casing ports

while the others of said rotor ports are masked by the casing port face.

6. A centrifugal pump as defined in claim 1, and wherein the number of said outwardly extending passages in the outlet diffuser means is equal to the number of fluid distributing ports in the fluid inlet restrictor means, and said outwardly extending passages communicate with the main outlet passage through a passage formed in the casing.

7. A centrifugal pump as defined in claim 1, and wherein said port faces of the casing and rotor are plane surfaces.

8. A centrifugal pump as defined in claim 1, and wherein said port faces of the casing and rotor are cylindrical.

9. A centrifugal pump as defined in claim 1, and wherein said fluid inlet restrictor means includes a cylindrical member mounted for rotation relative to the casing and having said port face thereon and said inlet ports therein, so that rotational movement of the cylindrical member changes the time of opening and closing of the rotor ports in relation to the opening and closing of the outlet passages in the rotor.

10. A restricted output centrifugal pump which comprises a casing having an inlet passage and an outlet passage, a rotor rotatably mounted in the casing, a number of spaced, outwardly extending fluid passages in the rotor, the last mentioned passages having inlet ends adapted to receive fluid from said inlet passage, a fluid inlet restrictor means for restricting the ingress of fluid from said inlet passage to predetermined ones of the rotor passages while preventing the ingress of fluid to the remaining rotor passages, the number of said predetermined ones of the rotor passages being less than the number of the remaining rotor passages, a fluid outlet diffuser means which permits the egress of fluid from the rotor passages to which fluid has been supplied from the inlet restrictor means while preventing the egress of fluid from the remaining rotor passages, and means for varying the output of the pump, the last mentioned means including angularly adjustable means in the inlet restrictor means which varies the timed relation of the opening and closing of said rotor passages in the restrictor means with respect to the opening and closing the rotor passages in the outlet diffuser means.

11. A centrifugal pump as defined in claim 1, wherein means are provided for preventing liquid which enters said casing through said main inlet reaching the central part of said rotor.

12. A centrifugal pump as defined in claim 1, wherein means are provided whereby the suction of the pump is utilized to evacuate the interior of the casing on one side of said rotor.

13. A centrifugal pump as defined in claim 1, wherein means are provided whereby the suction of the pump is utilized to evacuate the interior of the casing on both sides of said rotor.

14. A centrifugal pump as defined in claim 1, wherein said rotor is formed with a central recess providing said port face of said rotor, and wherein said fluid restrictor means comprises a hollow restrictor member which is engaged in said recess and is formed with a port face contiguous to said port face of said rotor, said restrictor means being formed with means for preventing the liquid which enters said casing through said main inlet reaching the central part of said rotor.

15. A centrifugal pump as defined in claim 14, wherein said last mentioned means consists of an

end closure wall of said restrictor member which is spaced from the central part of said rotor.

16. A centrifugal pump as defined in claim 14, wherein said last mentioned means consists of an end closure of said restrictor member, and wherein a port formed in said member provides communication between said main inlet and the interior of said casing at the front of said rotor.

17. A centrifugal pump as defined in claim 14, wherein said last mentioned means consists of an end closure of said restrictor member, and wherein a port formed in said member provides communication between said main inlet and the interior of said casing at the front of said rotor, communication between the interior of the casing at the rear of said rotor and said main inlet being provided by a port in said end closure and a port in said rotor.
